(57) CLAIM

The ornamental design for a storage cart as shown and described.

DESCRIPTION

FIG. 1 is a top, front, right side perspective view of a storage cart, showing our design.

FIG. 2 is a bottom, rear, left side perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof; and,

FIG. 8 is a bottom plan view thereof.

The broken lines depict portions of the storage cart that form no part of the claimed design.
